(57) **CLAIM**

The ornamental design for an electronic display for a wearable device with transitional graphical user interface, as shown and described.

DESCRIPTION

FIG. 1 is a front view of a first image of an electronic display for a wearable device with transitional graphical user interface, showing our new design;

FIG. 2 is an enlarged front view of the first image thereof; FIG. 3 is a front view of a second image thereof; and, FIG. 4 is an enlarged front view of the second image thereof. The appearance of the graphical user interface transitions sequentially between the images shown in FIGS. 1 and 3 and FIGS. 2 and 4, respectively. The process or period in which one image transitions to another forms no part of the claimed design.

The dashed broken line showing an electronic display for a wearable device in FIGS. 1 and 3 forms no part of the claimed design. The dash-dot-dash line labeled 2 in FIG. 1 and labeled 4 in FIG. 3 indicates the enlarged portions shown in FIGS. 2 and 4, respectively. The dash-dot-dash line forms no part of the claimed design.

1 Claim, 4 Drawing Sheets
